COOLING DEVICE FOR ELECTRIC
DISCHARGE TUBESHerre Rinia, Eindhoven, Netherlands, assignor to
Hartford National Bank and Trust Company,
Hartford, Conn., as trusteeApplication May 7, 1948, Serial No. 25,705
In the Netherlands June 18, 1947

5 Claims. (Cl. 250—27.5)

1

This invention relates to a cooling device for an electric discharge tube comprising a cylindrical cooled wall which is provided with a number of cooling vanes extending substantially at right angles to this wall and parallel to the generatrices of this wall, the cooling medium being supplied and/or carried off respectively through at least one channel which extends transversely to the direction of length of the cooling vanes. The invention furthermore relates to an electric discharge tube adapted to be cooled in such a device.

If the length of the cooling vanes in a cooling device of the character indicated above exceeds a given value, it is very difficult to solder or to weld a large number of closely adjacent cooling vanes to the cooled wall in such manner that an intimate thermal contact is ensured throughout their length. Both the cooled wall consisting of a material having a high thermal conductivity and the cooling vanes of thin sheet metal usually exhibit unevennesses, owing to which the cooling vanes do not directly engage the wall throughout their length. This is true whether the vanes are each secured individually to the cooled wall or are united in some way to form a zigzag band.

It has therefore, proved advantageous to make the cooling vanes not too long, thus providing a number of rings of cooling vanes side by side on the cylindrical cooled wall.

However, a new difficulty arises with an arrangement as described. The cooling vanes of the various rings will, in general, not be in line with each other, so that a stream of cooling medium passing in a longitudinal direction of the vanes from one ring of cooling vanes to the other experiences a high resistance. The invention overcomes the latter disadvantage and yields definite advantages.

In a cooling device for an electric discharge tube comprising a cylindrical cooled wall provided with a number of cooling vanes which extend substantially at right angles to this wall and parallel to the generatrices thereof the cooling medium is supplied and/or carried off respectively through at least one channel extending transversely to the direction of length of the cooling vanes which, according to the invention, are arranged in a number of rings arranged side by side, with the vanes in end-wise relationship, the separation between two rings being in each case centrally located in front of a channel which may serve either as a supply or as a discharge channel. The separation between

2

the rings of vanes then constitutes, in addition, the partition between the opposite streams of cooling medium associated with the supply or discharge channel, respectively, in situ.

3 If the cooling vanes are of a comparatively large size radial, it is desirable that the stream of cooling medium should penetrate throughout the length to the bottom of the spaces between the cooling vanes. This can be achieved by leaving some clearance between the rings of cooling vanes, so that a channel, into which the clearances between the vanes open, is formed all over the periphery of the cylindrical cooled wall. If, however, the cooling vanes are only of a small

15 radial size, it is advisable to provide partition walls between the rings of cooling vanes, for example by providing, between the adjacent rings of vanes a flat ring which fits around the cylindrical cooled wall.

20 It will, in general, be sufficient to press the rings of cooling vanes against each other in longitudinal direction. Since the cooling vanes of the various rings are not in line with each other, a partition wall for the flow of cooling medium between the adjacent rings is thus formed, as indicated above. Furthermore, the fact that the cooling vanes of the various rings are not in alignment results in that in these areas solder will more readily adhere than between the vanes themselves.

25 In general, however, this is not objectionable, since the partition between the rings of vanes serves as a separation between the currents of air. Consequently, there is no objection to clamping the cooling vanes, whether united to form a zigzag band or not, about the cooled wall and to plunging the assembly into a solder bath, so that the time consuming soldering of the vanes or rings of vanes each individually is disposed of.

30 The rings of vanes are preferably formed into zigzag bands in the manner indicated in U. S. patent specification No. 616,421, now abandoned, according to which the clearance between the parts of a zigzag band is removed by pressure on the side of the cooled wall.

35 The above-described system of arranging the cooling vanes in a number of rings has the advantage that cooling vanes of identical length can be used for cooled walls of different length, viz., by modifying the number of rings. This results in a reduction of manufacturing expenses, since it is not necessary to provide rings with different-size vanes for cooled discharge tubes of different size.

In order that the invention may be more clearly understood and readily carried into effect, it will now be described more fully with reference to the accompanying drawing, in which Fig. 1 is a side-view of a cooling device comprising an electric discharge tube according to the invention with the wall partly broken away, and Fig. 2 is a cross-section of the same device on the line II-II in Fig. 1.

In the drawing, the reference numeral 1 designates the glass wall of the electric discharge tube, which is otherwise not essential. The reference numeral 2 designates the circular-cylindrical metal anode to which rings of cooling vanes 3 are secured. Around the cooling vanes is provided a number of annular channels 4 which communicate at one side with a common supply pipe 5. The wall of three of the annular channels 4 is partly broken away to show the relative position of the rings of vanes. The reference numeral 6 designates the annular channel formed between two spaced rings of vanes, 7 designating a flat ring arranged between two rings of vanes and 8 denoting the drops of solder left between two rings of vanes pressed together. The exhaust cooling-air flows between the channels 4 freely into the open air. The same arrangement could be used for cooling the wall 2, if pipe 5 were connected to a suction device and thus used as a discharge pipe, while fresh air is sucked in between the channels 4.

What I claim is:

1. A cooling device for an electron discharge tube of the type having a cylindrical wall to be cooled, cooling vanes extending substantially at right angles to said wall and parallel to the generatrices thereof, said device comprising a plurality of channels for the exchange of cooling medium, said channels extending transversely to the direction of said cooling vanes, and a plurality of adjacent rings of said cooling vanes, with separations between said rings of vanes, each of said separations being centrally disposed in front of one of said exchange channels.

2. An electron discharge tube having an external wall to be cooled and including a cooling device of the type having cooling vanes extending substantially at right angles to said wall and parallel to the generatrices thereof, said device comprising a plurality of channels for the exchange of cooling medium, said channels extending transversely to the direction of said cooling vanes, and a plurality of rings of said cooling vanes, said rings of vanes being arranged side by side, with slight separations, over a substantial length of the tube wall with said vanes in endwise relationship, each of said separations being centrally disposed in front of one of said exchange channels.

3. An electron discharge tube including a cooling device having cooling vanes of the type as claimed in claim 2, said device comprising a plurality of rings of said cooling vanes, said rings of vanes being arranged side by side in slightly spaced relationship over a substantial length of the tube wall with said vanes in endwise relationship, a plurality of channels extending transversely to the direction of the cooling vanes, said

5 rings of vanes having their spaced ends centrally arranged with respect to said channels, and a common supply pipe for conveying cooling medium to said channels.

10 4. An electron discharge tube including a cooling device having cooling vanes of the type as claimed in claim 2, said device comprising a plurality of rings of said cooling vanes, said rings of vanes being arranged side by side in slightly spaced relationship over a substantial length of the tube wall with said vanes in endwise relationship, a plurality of channels extending transversely to the direction of the cooling vanes, said rings of vanes having their spaced ends centrally arranged with respect to said channels, and a common pipe for the discharge of cooling medium from said channels.

15 5. An electron discharge tube including a cooling device having cooling vanes of the type as claimed in claim 2, said device comprising a plurality of rings of said cooling vanes, said rings of vanes being arranged side by side in slightly spaced relationship over a substantial length of the tube wall with said vanes in endwise relationship, a plurality of channels extending transversely to the direction of the cooling vanes, said rings of vanes having their spaced ends centrally arranged with respect to said channels, and a common pipe for the discharge of cooling medium from said channels.
